UNITED STATES PATENT OFFICE.

GREENLEAF WHITTIER PICKARD, OF NEWTON CENTER, MASSACHUSETTS, ASSIGNOR
TO WIRELESS SPECIALTY APPARATUS COMPANY, OF BOSTON, MASSACHUSETTS, A
CORPORATION OF NEW YORK.

ELECTRICAL CONDENSER.

Application filed October 8, 1920. Serial No. 415,472.

This invention relates to electrical condensers and in particular to high tension condensers for general use but especially adapted for use in radio communication.

5 In condensers heretofore in use, the condenser stack generally has been arranged in its casing vertically, resting on the bottom and secured in the casing by means of a cover of insulating material which has

10 proved unsatisfactory for the purpose of maintaining the high pressure necessary for the proper operation of the condenser which requires that the sheets of dielectric, generally mica, and foil, preferably tinfoil, be

15 maintained in intimate contact. Such condenser comprises a number of sections connected in series, the low potential section being connected to the casing, while the high potential section is connected to a suitable

20 terminal projecting through the cover.

The object of the present invention is to provide a compact, durable condenser in which the stack is constantly maintained under the highest practical compression.

25 In particular the object of the invention is to provide a construction in which the use of insulating material under strain for the purpose of compression (of the condenser stack; as heretofore, as of a top casing-cover of insulating material) is avoided and in which the sides of the casing receive the thrust of compression, compactness being obtained by reducing to a minimum the amount of insulation used.

30 Furthermore, the invention is an improvement upon the disclosure of United States patent to Dubilier No. 1,229,914 of 1917.

Yet more particularly the invention relates to metallic means for combining the 35 condenser stack with a metal casing, mechanically, electrically and thermally, whereby the stack is supported and clamped by the metal casing which encloses it, being supported in such manner as to have certain parts connected with the casing and other parts spaced and insulated from the casing; and said metallic means include devices located at the ends of the stack connecting it with the casing, and also particularly, a metal pressure and connector plate located 40 in the middle of the stack and connected

with a condenser terminal projecting thru the enclosing casing to the exterior thereof but suitably insulated therefrom.

The invention consists further in details 55 of construction and combination of parts hereinafter more particularly described and claimed.

In the accompanying drawings, which form a part of the specification, 60

Figure 1 is a sectional elevation of one embodiment of the invention.

Fig. 2 is a sectional elevation thereof taken on the line 2—2 of Fig. 1, looking in the direction of the arrows. 65

Fig. 3 is a sectional elevation of a modified form of the invention in which the casing is shown inclined.

Fig. 4 is a sectional elevation of the construction shown in Fig. 3 taken on the line 70 4—4 of Fig. 3, looking in the direction of the arrows.

Fig. 5 is a sectional elevation of still another modification.

In the embodiment of the invention shown 75 in Figs. 1 and 2, there is provided a suitably strong box-like metallic casing 1 with vertical sides 2^a which are held rigid by the bottom. Within this casing is placed the stack 2 which is arranged transversely of 80 or parallel to the bottom of the casing; that is, the individual sheets of foil and dielectric composing the stack are arranged vertically with reference to the bottom and spaced therefrom sufficiently for purposes of insulation.

Stack 2 may consist of one or two parts, such as parts 3 and 4, arranged end to end transversely of the casing, the two parts being connected in parallel at adjacent ends 5 centrally of the casing and each part 90 3 and 4 comprising a plurality of sections 6 connected in series at alternate ends 7 and provided with separators 8 between the sections projecting beyond adjacent unconnected ends and beyond the connections. Means 95 is provided in the present invention which co-operates with the opposite sides 2^a of the casing for clamping the stack in place within the casing and exerting high pressure on the stack to maintain the sheets of dielectric and foil in intimate contact. This means in the embodiment of Fig. 1 comprises a pair of 100

metallic wedges 9 and 10 which are placed centrally within the casing and in the present embodiment between and engaging the inner adjacent ends 5 of the two parts 3 and 4 of stack 2 and having a surface sufficiently great to cover the adjacent surfaces of the adjacent ends 5 of the two parts 3 and 4. The outer ends 11 and 12 of the stack 2 engage the vertical opposite walls 2^a of the casing 2 substantially as shown, the stack being highly compressed between the wedges 9 and 10 and the sides of the casing, the pressure being transmitted uniformly over the entire surface of the sheets. In assembling the stack in the casing, after the wedge 9 is in place, the wedge 10 may be driven in by any suitable means compressing either the part 3 or 4, or both, against the sides 2^a of the casing 1, which should be sufficiently strong for this purpose, thus exerting a high pressure on the stack and maintaining the sheets of foil and dielectric in intimate contact uniformly throughout their surfaces, the pressure being applied at right angles to the surfaces of the sheets. The inner ends 5 of the two parts 3 and 4 or the innermost sections 6 are electrically connected to the wedges 9 and 10 which constitutes a high potential point intermediate of the stack and sufficiently spaced from the casing 1 for insulation purposes. A suitable lead 13 connects these wedges 9 and 10 to a high potential terminal 14 projecting through insulating cover 15, whereby the two parts 3 and 4 are connected in parallel. The outer ends 11 and 12 of the stack 2 are at substantially the same potential and electrically connected to the casing 1, which constitutes the low potential terminal whereby the stack may be clamped through the instrumentality of the sides of the casing without the introduction of insulation for insulating the ends from each other, although it is practicable there to employ under compression any of the commonly used insulating materials.

In effect, the stack 2 comprises two separate stacks or parts 3 and 4, each part having its low potential end near the casing and its high potential point centrally of the casing. Compression is maintained on each stack or parts 3 and 4 by the wedges 9 and 10 which exert a thrust on opposite walls of the casing through the two stacks or parts 3 and 4, and support the stack in its position electrically spaced from the metal of the casing. Also the intermediate members 9, 10 of Figs. 1 and 3 and member 24 of Fig. 5 are useful mechanically in distributing the applied pressures more uniformly throughout a long stack by reason of their effective mechanical splitting of the entire stack into two shorter mechanically separated stacks; and such intermediate members are useful electrically in providing means for connecting the adjacent ends of the shorter stacks to

the exterior terminal 14, the surfaces of such intermediate metal members constituting practical means for the soldering thereto of the foils projecting from sections of the two shorter stacks adjoining the intermediate metal member; and such intermediate metal members are useful thermally in being good thermal conductors absorbing heat transmitted thereto longitudinally from both adjacent short lengths of the entire stack. 75

It will thus be seen that there is provided a stack in two parts 3 and 4, the two parts being connected in parallel and the individual sections of each part being connected in series with the outer ends 11 and 12 at the same potential as that of the casing, whereby the casing may be utilized as a part of the clamping means without excessive insulation, or insulation under tensile strain, while the central portion 9, 10 of the 85 clamping means, i. e., the part most remote from the casing and hence suitably insulated therefrom via the stack itself, is the high potential point of the condenser.

The stack or the parts 4 and 5 thereof may 90 be manufactured and built up in any suitable manner, though it is preferable that they be built up of alternate sheets of foil of opposite polarity, preferably tinfoil, and dielectric, preferably mica, with proper precautions 95 for removing air and moisture and highly compressing the stack during manufacture. The process may be carried out by coating each sheet with melted wax such as paraffin during the building, then submitting the 100 stack of sheets to high pressure of the order of thousands of pounds to force out the wax, then separating the stack into sections and making the connections, then applying high pressure to the stack and treating 105 it with wax, as more fully described in my co-pending application Serial Number 380, 919, filed May 12, 1920. After the stack as above treated is placed in the condenser casing 1 in the manner above described, the casing may be filled with any suitable embedding wax 16 such as paraffin or a mixture 110 of paraffin and carnauba wax, either with or without the aid of vacuum and the cover is then applied. 115

The form disclosed in Figs. 3 and 4 is slightly different from the form disclosed in Figs. 1 and 2, inasmuch as the casing 1^a is there shown as having inclined sides 2^b, and between the outer ends 11^a and 12^a of the 120 stack 2^c and casing 1^a are placed wedges or abutments 17 and 18 of any suitable material such as metal, which also may be integral with the casing, for the purpose of providing a flat surface for uniformly engaging the 125 ends 11^a and 12^a of the stack throughout their surfaces.

Referring to Fig. 4, it will be seen that the sheets of mica 19 and foil 20 of the sections 6^a taper downwardly with their long edges 130

21 and 22 parallel to the sides of the casing, thereby giving the sheets a keystone shape. The separators 8^a are cut in similar manner. A uniform insulation distance between the edges of the foil and the casing is thus maintained. In other respects, the construction of Figs. 3 and 4 is like that of Figs. 1 and 2.

The wedge specific forms of Figs. 1-2 and 10 3-4 constitute the subject matter of my divisional Patent 1,503,765 dated August 5, 1924.

In Fig. 5 is illustrated a modified form of clamping means for maintaining the stack 15 2^d under compression within the casing 1^c having sides 2^e. In this embodiment, the stack 2^d is in two parts 3^e and 4^e, electrically connected in parallel, each part being made up of a plurality of sections 6^e connected 20 in series and provided with separators 8^e between the sections as above described. The stack 2^d is placed horizontally or transversely within the casing in the same manner as the stacks above described with the 25 inner ends 5^e of the parts 3^e and 4^e facing each other and separated by and engaging a central metal plate or pressure member 24 of about the same surface area as the ends of the stack and to which the adjacent sections 30 are electrically connected in parallel forming a centrally located high potential point of the condenser. The outer ends 11^e and 12^e of the stack or parts thereof are provided with metal pressure plates 25 and 26 engaging the same, interposed between the ends of the stack and the casing and forming abutments for adjusting screws 27 and 28 interposed between the plates 25 and 26 and the casing, extending 40 through the opposite sides 2^e of casing 1^c and engaging the abutments or pressure plates 25 and 26. The pressure plates 25 and 26 are provided with recesses 29 into which the inner ends of the screws fit for 45 holding the plates and stack in place within the casing and electrically separated therefrom. The outermost sections or outer ends 11^e and 12^e of the stack 2^d or parts are at the same and equal potential, and electrically connected to the casing which constitutes the low potential terminal. This 50 electrical connection to the casing may be made through the pressure plates 25 and 26 as shown or by separate leads to the casing. By means of either adjusting screw 27 or 28 or both, a high degree of pressure may be maintained upon the stack or any part thereof, maintaining the sheets of the stack in intimate contact throughout their 55 surfaces and positioning or adjusting member 24 in either direction to centrally locate it within the casing in convenient relation to terminal 14^c. The adjustment of either screw 27 or 28 forces the stack against 60 the distant pressure plate which in turn con-

veys the thrust to the side wall of the casing. The stack shown in Fig. 5 may be treated with wax to remove air, etc., in any suitable manner, such as above described, and the final pressure is applied by the 70 screws 27 and 28 after the stack is placed in the casing. The casing may then be filled with any suitable embedding wax as above described. The metal plate 24 which constitutes the high potential point of the condenser and is located centrally within the casing is connected by a conductor 13^c to a high potential terminal 14^c, as above described, projecting through a suitable insulating cover 15^c of any suitable material having the requisite insulating qualities.

The condenser embodying this invention maintains the sheets of foil and dielectric in intimate contact under high pressure securing at the same time compactness and durability. In the embodiments illustrated, the outer ends of the stack or parts are at equal and low potential and electrically connected to the casing which constitutes the 85 low potential terminals, while the intermediate part of the stack constitutes the high potential part thereof. Thus there is provided a condenser which is strong and compact and in which the stack is maintained 90 under a high pressure without the necessity of excessive insulation in the clamp to insulate the ends from each other.

It is to be understood that the invention is not limited to the embodiments and features specifically shown and described herein, but that such embodiments and features are subject to changes and modifications without any departure from the spirit of the invention.

Having now described the invention, what is claimed as new and what it is desired to protect by Letters Patent of the United States is as follows.

1. In an electrical condenser, the combination with a stack of sheets of dielectric material and conducting foils, of a boxlike metal casing therefor the walls of which are held substantially rigid by the casing-bottom; a condenser terminal extending from the stack out through the casing at a point intermediate the walls thereof and insulated from the metal of the casing; the stack being positioned in the casing with its ends facing opposite rigid casing-walls and with the edges of its sheets spaced from the metal of the casing to be electrically insulated therefrom when the condenser is connected in use in its circuit; and pressure devices located inside the casing between the stack and the opposite casing-walls, said pressure devices being constructed and arranged to cause the stack to tend to force said casing-walls away from one another and by the rigidity thereof hold the stack under its 130

service conditions of compression and position separated from the metal of the casing; and said pressure devices being movable independently of one another to permit centralizing the stack with respect to said condenser terminal, in the act of putting the stack under its service compression.

2. In an electrical condenser of the stack-sheet type, the combination with a box-like 10 casing having metal bottom and sides, of a series sectional stack arranged transversely therein with its ends adjacent to and electrically connected with two opposite metal sides of the casing and its sides spaced from 15 the bottom and the other sides of the casing; a condenser terminal extending from the stack through and insulated from the metal casing; a conducting member of substantial thickness, mass and stiffness interposed in 20 the middle of the stack and having flat opposite surfaces engaging the adjacent ends of the two portions of the stack on opposite sides of such conducting member, said conducting member being electrically connected 25 to said condenser terminal; and a device located between an outer end of the stack and an adjacent side of the casing and holding the stack under compression and in position suspended in the casing.

3. In an electrical condenser of the stack-sheet type, a box-like metal casing, a condenser terminal extending from the stack and insulated from said casing, the stack being in two parts located end to end inside 35 the casing; an intermediate conducting member of substantial thickness, mass and stiffness and located between the parts of the stack, to which conducting member like-potential portions of the adjacent stack-parts are electrically connected; said intermediate member being connected to said condenser terminal; and means electrically connecting the outer ends of the stack to said metal casing and holding the stack 45 under compression of the sides of the casing.

4. In a condenser, a metal casing having sides, a condenser stack therein comprising two parts connected in parallel, each part comprising sections connected in series, providing ends of low potential and an intermediate point of high potential, the casing being at the same potential as the ends of the stack, and means co-operating with the sides of the casing for compressing the stack 55 therein, said means comprising pressure devices located respectively between the stack-ends and casing-sides and movable independently of one another permitting localization of the stack in the casing in the direction of the length of the stack.

5. In an electrical condenser, the combination with a stack of sheets of dielectric material and conducting foils, of a boxlike metal casing therefor the walls of which 60 are held substantially rigid by the bottom;

said stack being positioned in such casing to have its ends facing opposite walls thereof and the edges of its sheets spaced from the bottom and the other walls of the casing; and means located inside the casing and between the ends of said stack and said opposite rigid walls and movable by one another by way of the intervening stack, for maintaining the sheets of the stack in intimate contact with one another over substantially their entire surfaces by holding them together under compression, said means being constructed and arranged to bear against said opposite walls respectively and to engage substantially the entire areas of the ends of the stack and to cause the stack to tend to force said walls away from one another; said means being constructed and arranged to be independently movable toward one another, while bearing against said opposite walls, into a position wherein the sheets of the stack are maintained under the desired high compression; and said means being constructed and arranged cooperatively with said walls to support the stack in its said position separated from the metal casing.

6. In an electrical condenser, the combination with a stack of sheets of dielectric material and conducting foils, of a boxlike casing therefor the walls of which are held substantially rigid by the bottom; the stack being positioned in said casing with its ends facing opposite walls thereof; and means for maintaining the sheets of the stack in intimate contact with one another over substantially their entire surfaces by holding them together under compression, said means comprising pressure plates engaging substantially the entire areas of the two ends of the stack and movable by one another by way of the stack, and means engaging each pressure plate, bearing against the respective opposite casing-walls, and constructed to operate with the pressure plates to support the stack in position away from the other walls of the casing and to permit the respective places of engagement with the pressure plates to be independently movable each toward the other wall while such engaging means continues to bear against said walls, whereby the plates or either of them may be brought into final position to cause the stack to tend to force said opposite walls away from one another and thereby maintain the sheets of the stack in intimate contact with one another under the desired high compression.

7. In an electrical condenser, a casing, a stack within the casing in a plurality of parts arranged end to end, a conducting member of substantial thickness, mass and stiffness, and mounted between the parts and receiving the thrust thereof at the inner ends, and means co-operating with the cas- 130

ing and the outer ends of the stack for compressing the parts against said conducting member.

8. In an electrical condenser, the combination with a stack comprising sheets of dielectric material and conducting foils, of a boxlike casing therefor the walls of which are held substantially rigid by the bottom, the stack being positioned in the casing with its ends facing opposite casing-walls; and means for maintaining the sheets of the stack in intimate contact which comprises three members, one of which has substantial thickness, mass and stiffness and is located between two parts of the stack and the other two of which are located respectively between the ends of the stack and opposite casing-walls, said three members being constructed and arranged to cause the stack to tend to force said walls away from one another and thereby itself and its parts be held under compression between such walls. 45

9. In an electrical condenser, a casing, and a stack within the casing in a plurality of parts arranged end to end and having an intermediate conducting member of substantial thickness, mass and stiffness, and located between the parts, said stack-parts being compressed between the walls of the casing and said conducting member. 55

10. In an electrical condenser, a casing, a stack within the casing in a plurality of parts, an intermediate pressure member between the parts, pressure plates upon the outer ends of the parts and screws threaded into the casing and engaging the pressure plates for compressing the stack against the intermediate pressure member and adjusting the stack and pressure member in opposite directions. 65

11. In an electrical condenser, a metal casing having an insulating portion, a stack

within the casing comprising parts having sections connected in series, an intermediate metal pressure member between the parts to which the inner ends of the parts are electrically connected, pressure plates on the outer ends of the parts, screws threaded in the casing and engaging the pressure plates for compressing the parts and adjusting them in opposite directions, the outer ends of said parts being electrically connected to the casing, and a terminal projecting through said insulating portion and connected to said intermediate member. 50 55

12. In an electrical condenser, a casing having a terminal therein, a stack in a plurality of parts arranged end to end within the casing, an intermediate metal pressure member of substantial thickness between the parts to which like terminals of the parts adjacent said member are electrically connected, said pressure member being electrically connected to said casing terminal, and means for compressing the stack and adjusting the same with the intermediate member in opposite directions to properly position the same within the casing. 60 65

13. In an electrical condenser, a metal casing, a stack arranged within the casing and having a plurality of parts each comprising sections connected in series, a metal member of substantial thickness and located between said parts to which the inner ends of the parts adjacent said member are electrically connected, said parts being compressed between said metal member and the walls of the casing respectively, the outer ends of said parts adjacent the casing being electrically connected thereto, and a terminal projecting through said casing and insulated therefrom and electrically connected to said intermediate metal member. 70 75 80

GREENLEAF WHITTIER PICKARD.
